UNITED STATES PATENT OFFICE.

MICHAEL H. BYRNE, OF ASHLAND, WISCONSIN.

LOADING APPARATUS.

1,144,460.

Specification of Letters Patent. Patented June 29, 1915.

Application filed December 12, 1914. Serial No. 876,901.

To all whom it may concern:

Be it known that I, MICHAEL H. BYRNE, a citizen of the United States, residing at Ashland, in the county of Ashland and State of Wisconsin, have invented certain new and useful Improvements in Loading Apparatus, of which the following is a specification, reference being had to the accompanying drawings.

10 This invention relates to certain improvements in conveyers and has relation more particularly to a device of this general character especially designed and adapted for use in connection with logs or the like; and 15 an object of the invention is to provide a device of this kind having novel and improved means whereby the logs or the like may be conveyed in substantially an automatic manner from their source of supply 20 to a predetermined place of delivery.

Furthermore, it is an object of the invention to provide a novel and improved device of this general character adapted to discharge the logs or the like within a vehicle and provided with means whereby its discharge extremity may be readily adjusted relative to the vehicle and the load placed thereon.

The invention consists in the details of 30 construction and in the combination and arrangement of the several parts of my improved conveyer whereby certain important advantages are attained and the device is rendered simpler, less expensive and otherwise 35 more convenient and advantageous for use, all as will be hereinafter more fully set forth.

The novel features of the invention will be carefully defined in the appended claim.

40 In order that my invention may be the better understood, I will now proceed to describe the same with reference to the accompanying drawings, wherein—

Figure 1 is a view in side elevation, with 45 certain parts in section, of a conveyer constructed in accordance with an embodiment of my invention; Fig. 2 is a front elevational view of the device as disclosed in Fig. 1; Fig. 3 is a fragmentary view in top plan, 50 with parts in section, of the means whereby an extremity of the conveyer may be raised or lowered; Fig. 4 is an enlarged fragmentary sectional view illustrating a guiding

means herein embodied; and Fig. 5 is an enlarged fragmentary view in side elevation 55 of one of the chains herein included, and illustrating in detail the mounting of an engaging arm thereon.

As disclosed in the accompanying drawings, 1 denotes a supporting structure of 60 any preferred arrangement and herein disclosed as positioned adjacent a water front and having disposed along its water side a shaft 2 with which is pivotally engaged through the medium of suitable yokes, as 65 indicated at 3, in Fig. 1, the elongated parallel beams B, the lower extremities whereof being tied or connected by the transversely disposed beam 4 adapted to rest upon suitable piling 5 whereby a support for the 70 lower extremities of the beams B is afforded. The beams B are also tied or connected one with the other adjacent their upper extremities by the transverse beam 6. The opposite extremities of the beams B have 75 rotatably engaged therewith the transversely disposed shafts 7 provided with the sprockets 8 around which are disposed the endless chains 9, the lower stretches of such chains being disposed beneath the transverse 80 beams 4 and 6 and each of such chains has coacting therewith an idler roller 10 engaging the lower stretch thereof in order to carry the slack of the chain. I wish to state that I desire to be understood as limiting 85 myself to no particular form of idler 10 and I also wish to state that if preferred the same can be omitted.

At predetermined intervals therealong, 90 each of the chains 9 is provided with the spaced links 11 and 12 having projecting outwardly therefrom the ears 14 and 15, respectively. Pivotally engaged with the ears 15 are the outstanding arms 16 having pivotally secured thereto adjacent their outer extremities the brace arms 17 which in turn are pivotally engaged with the ears 14. By this arrangement it will be readily perceived that the arms 16 are normally disposed and maintained at substantially right 95 angles to the chain but are capable of unhampered travel around the sprockets 8.

The corresponding arms of the several chains are disposed in transverse alinement so that the logs which have been congregated adjacent the supporting structure 100 105

may be readily engaged by said arms and conveyed upwardly of the beams B and suitably discharged, said discharge being preferably within a vehicle positioned below the delivery end of the beams B.

5 In order that the forward extremities of the beams B may be raised or lowered in accordance with the requirements of practice, I find it of advantage to have each of 10 said beams composed of two sections 18 and 19, the adjacent extremities whereof being pivotally or hingedly connected, as at 20, with the adjacent ends 21 thereof disposed on such inclinations as to readily permit 15 relative movement of the sections 18 and 19.

15 In order that the upper sections 19 of the beams may be readily raised or lowered, I have pivotally engaged with the transverse beam 6, as indicated at 22, the threaded shafts 23 having operatively engaged therewith the sprocket wheels 24 whereby it will be readily perceived that upon requisite rotation of the sprockets 24 the shafts 23 will be moved in a direction to either raise or lower 25 the sections 19 of the beams B. This adjustment of the sections 19 is necessary in order to compensate for the vertical increase of the load formed within the vehicle or the like, it being understood that the sections 19 are in their lowermost position at the initial 30 formation of the load in order that the logs or the like will drop a minimum of distance in order to avoid undue shock being imparted to the vehicle. The sprockets 24 are 35 operatively connected by a conventional sprocket chain 25 whereby it will be perceived that said shafts 23 will be caused to rotate in unison and in the same general direction. While any means may be employed for imparting the requisite rotation to the shafts 23, I herein disclose the chain 25 as operatively engaged with a sprocket 26 fixed to a vertically disposed shaft 27 coupled, as at 28, with a suitable source of 40 power. Also coacting with the chain 25 and in close proximity to the sprocket 26 and engageable with the chain 25 at a side opposite to the sprocket 26 is the tension sprocket 29. I also find it of advantage to 45 provide means whereby the beams B are held against undue lateral displacement and, as herein set forth, I accomplish this purpose through the medium of the upright 50 pivotally engaged, as at 31, with the supporting structure 1 and movable in a direction longitudinally of the beams B. The inner face of the upright 30 is provided 55 with a track-way 32, herein disclosed as of T-shape in cross section, and with which is 60 operatively engaged the slide 33 herein disclosed as substantially C-shape in cross section and coacting with the track-way 32 in a conventional manner. As herein embodied, the slide 33 is provided with an arm 65 or extension 34 operatively engaged, as at

35, with a bracket 36 depending from and suitably secured to the adjacent extremity of the transverse beam 6. By this arrangement, it will be readily perceived that an effective reinforcing means is provided 70 which serves to maintain the beams B against undue lateral movement but which at the same time does not interfere with the vertical adjustment of the beams.

The idler roller 10, hereinbefore referred 75 to, is loosely mounted on the shaft 37 driven from a suitable source of power and provided with a sprocket 38 around which is disposed a driving chain 39 which is also directed around a sprocket 40 affixed to the 80 upper shaft 7 whereby it will be readily perceived that the requisite rotation may be imparted to said shaft 7 for properly operating the chains 9. As herein disclosed, the stretches of the chain 39 are disposed at opposite sides of the transverse beam 6 with the upper stretch operatively engaged with a sprocket 41 fixed to an idler shaft 42 supported by certain of the beams B and disposed transversely thereof. I also find it of 85 advantage to provide the transverse beam 6 with a forwardly projecting arm 43 disposed in substantial parallelism with the beams B and terminating in a bearing 44 for the uppermost shaft 7 and positioned in 90 close proximity to the sprocket 40 whereby said shaft 7 at its drive connection will possess a maximum of strength.

95 As herein set forth, the beams B are of such a length as to have their lower extremities terminate below the water level so that the arms 16 will be caused to operatively engage the logs or the like which have been properly floated into relation with the lower extremity of the beams B whereby it will be 100 readily perceived that such logs or the like may be conveyed to a proper point of discharge in substantially an automatic manner.

105 From the foregoing description, it is 110 thought to be obvious that a conveyer constructed in accordance with my invention is of an extremely simple and comparatively inexpensive nature and is particularly well adapted for use by reason of the convenience and facility with which it may be assembled, and it will also be obvious that my invention is susceptible of some change and modification without material departure 115 from the principles and spirit thereof and for this reason I do not wish to be understood as limiting myself to the precise arrangement and formation of the several parts herein shown in carrying out my invention in practice.

120 I claim:

125 A device of the character described comprising a support, a frame capable of movement relative to said support, a cross beam connecting the upper extremity of the 130

frame, means coacting with the cross beam for raising and lowering said upper extremity of the frame, an upright pivotally mounted upon the support and movable in a 5 direction longitudinally of the frame, and a slideable connection between said upright and the adjacent extremity of the cross beam.

In testimony whereof I hereunto affix my signature in the presence of two witnesses.

MICHAEL H. BYRNE.
